UNITED STATES PATENT OFFICE.

CHARLES H. BARNES, OF ILION, NEW YORK.

TRIGGER MECHANISM FOR FIREARMS.

Application filed April 23, 1923. Serial No. 634,082.

This invention relates generally to firearms and more particularly to that class of firearms having a set trigger mechanism for discharging the same.

5 A broad object of the present invention is to provide a trigger mechanism of the type having a main trigger and an auxiliary or set trigger pivoted on the main trigger which is reliable in operation, easily operated, inexpensive to manufacture and which may readily be attached to the firearms now in use.

More specifically it is an object of the present invention to provide a trigger mechanism which normally requires an appreciable movement of the trigger to release the firing member to discharge the arm, with an auxiliary trigger which may be readily and quickly set to a position which will require 15 a less degree of movement and pressure of the set trigger to release the firing member.

In trigger mechanism of the class of firearms just described the full strain and compression of the firing-pin spring has been 20 exerted against the pivoted sear and in order to preclude the possibility of an accidental discharge of the firearm a large amount of bearing surface has been provided 25 between the cocking piece and the sear. This construction required a heavy pull as well as an appreciable movement of the trigger in order to release the sear from the 30 cocking piece against the full strain and compression of the firing-pin spring.

35 In certain kinds of shooting it is desirable that the gun be fired by a comparatively light pressure upon the trigger thus precluding the possibility of disturbing the accuracy of aim while discharging the gun. 40 In order to meet this requirement firearms are usually equipped with a second trigger known as a "set" or "hair trigger".

Certain constructions of set triggers heretofore applied to firearms required the invention 45 of a second trigger the pivotal point of which is separate and independent of the regular trigger and to so equip a firearm with this type of set trigger usually required a reorganization of parts and practically a 50 reconstruction of the trigger mechanism.

It is an object of the present invention to provide a set trigger in such a form that it can readily be applied to firearms now in general use in such a manner that the additional parts required can be readily applied 55 with little difficulty and require compara-

tively few changes in the parts already in use.

With these and incidental objects in view the invention consists in certain novel 60 features of construction and combination of parts, the essential elements of which are set forth in the appended claims, and a preferred form of embodiment of which is hereinafter described with reference to the 65 drawings which accompany and form part of the specification.

Of said drawings:

Fig. 1 is a fragmentary view in side elevation, partly in section, of a breech loading 70 firearm equipped with the present invention and showing the trigger mechanism cocked for firing the gun by a pull on the regular trigger.

Fig. 2 is a view similar to Fig. 1 showing 75 the set trigger adjusted so that the firearm may be discharged by a relatively light pull.

Fig. 3 is a top plan view of the trigger frame showing the adjustable sear block 80 and adjusting screw.

Fig. 4 is a view in perspective of the adjustable sear block showing the retaining spring in position.

Fig. 5 is a plan view of the underside of 85 the stock with the trigger guard removed showing the means for retaining the cylindrical spring housing in place.

For the purpose of illustration the present invention is shown applied to that type 90 of firearm known as the "Springfield", model 1917, rifle which has been used quite extensively in military service and to this end I have shown in the drawings this particular type of rifle. The trigger mechanism and associated parts of this type of rifle is shown and explained in detail in the patent to John D. Pedersen #1,355,417, Oct. 2, 1920, and for further details of construction reference may be had to the said 100 patent. It is to be distinctly understood that although this particular type of firearm has been shown, it is merely for the purpose of illustration and the inventive ideas are capable of being embodied in and applicable to firearms of other varieties. 105

As shown in Figs. 1 and 2 the "Springfield" rifle comprises a barrel secured to a "receiver" or main frame 9, having therein a breeching chamber. Slidably mounted and operable in the main frame 9 is a reciprocal breech bolt 10. The stock 11 has the 110

usual forestock 12 and shoulder portions 13 (neither of which are fully shown in the drawings.) The stock, frame and barrel are held assembled by the customary releasable fastenings, one of which is shown as a screw 14 passing through a trigger frame 15, a bushing in the stock and into a threaded portion of the rear of the main frame 9. The magazine, the rear wall 26 of which is shown, holds the usual supply of cartridges which are fed into the breech chamber when the breech bolt is reciprocated in a manner which is well known in the art.

Slidably mounted in the breech bolt 10 is a firing bolt 151 the forward end of which is provided with the usual spring pressed firing pin (not shown). The firing bolt 151 is also provided with a downwardly extending cocking piece 16 which is adapted to abut against a sear nose 17 of a sear lever 18 which is shown pivoted at 19 to downward extensions of the receiver 9. A helical sear spring 201 interposed between the frame 9 and one end of the sear lever 18 strongly actuates the other end upwardly, its upward movement being limited by a transverse pin 46 abutting against the frame so that the sear nose 17 will pass in front of the cocking piece when the firing bolt 151 is drawn rearwardly by virtue of the retraction of the breech bolt 10 in the operation of cocking the arm. When the arm is cocked and the breech bolt locked in "firing position" the firing pin will be held back 35 against the compression of its spring by the engagement of the cocking piece 16 and the sear nose 17. In order to effect disengagement of the sear nose and cocking piece to permit the firing pin to move forwardly 40 there is provided a releasing trigger 20.

The trigger 20 is pivoted substantially midway of the sear lever 18 by a transverse pin 21 and passes through the stock 11 and a slot 24 cut in the frame 15 provided with a trigger guard 25, the lower end of the trigger being formed with a curved finger piece 22. The upper end of the trigger is provided with a rearwardly extending cam portion 23 contacting with the lower edge of the main frame 9.

Assuming that the gun is closed and locked with the trigger 20 in the position in which it is shown in Fig. 1, it is apparent that when the trigger is pulled back in the ordinary manner by the finger piece the cam 23 upon its upper edge will rock upon the lower edge of the frame 9 compressing the sear spring 201 to the extent required for disengaging the sear nose 17 from the cocking piece 16 permitting the firing pin to spring forward under the influence of its spring to discharge the cartridge.

From the foregoing it is evident that in order to discharge the gun an appreciable movement of the trigger as well as a con-

siderable degree of pressure is required to disengage the sear nose from cocking piece. To permit firing of the gun by a comparatively light pressure upon the trigger a second or "set trigger" is provided. 70

The trigger 20 is provided with a longitudinal slot 27 within which is pivoted by a transverse pin 28 a set trigger 29 having a curved finger piece the contour of which is substantially the same as the finger piece 75 of the trigger 20. The set trigger is urged rearwardly to its normal or inoperative position by a helical spring 30. The forward part of the set trigger is equipped with a nose 31 provided with an engaging hook 80 32 and an adjusting screw 33.

Reference character 34 indicates a cylindrical spring housing in which is inserted a helical spring 35 abutting against a plunger 36 slidably mounted within the housing 85 34. The rearward end of the said housing is conoidal and engages a conical depression formed in the forward edge of the trigger 20. The plunger 36 abuts against a wall 26 of the magazine in a similar manner. 90 The spring housing is inserted in a slot 50 (Fig. 5) formed in the stock 11, the forward end of the housing being provided with a flange 51 abutting against a shoulder 52 formed at the end of the slot 50. This limits the rearward movement of the cylindrical housing 34 urged by the initial tension of the spring 35. It will be seen from an inspection of Fig. 1 that if trigger 20 be actuated during a regular operation a separation of the housing and trigger will occur and by providing this construction the conoidal end of the housing will be held in proper alignment for the reception of the conical depression when the trigger is 105 again cocked.

Pivoted within the trigger guard frame 15 by a transverse pin 37 is an adjustable sear block 38 provided with a slot 39 through which project the triggers, and a beveled nose 40 best shown in Fig. 4. In order to raise or lower the beveled nose 40 there is provided an adjusting screw 41 formed with a head 53, the shank of the screw passing through an open slot formed at the rear end 110 of the sear block and through the trigger guard frame 15 in order to permit an exterior adjustment of the sear block 38. The purpose of adjusting the sear block will appear later. The adjustable sear block is 120 further equipped with a wire spring 42 so arranged as to be movable with the sear block and provided with a bent hook 43 adapted to hook over the nose 32 of the set trigger when the latter has been adjusted to its "set" position.

When it is desired to operate the auxiliary or set trigger for accurate shooting the procedure is as follows. Pressure is applied to the rear edge of the finger piece of the trig- 130

ger 20 and the two triggers moved forwardly until the hook 32, which has in the meantime engaged the hook 43 of the spring 42, has been urged upwardly far enough to clear 5 the beveled nose 40, whereupon it snaps upwardly as shown in Fig. 2. While the trigger 20 has been moved forwardly a considerable amount of energy has been stored in the spring 35 the said spring tending to 10 force the trigger rearwardly but being prevented by the engagement of the hook 32 and beveled nose 40. After the engagement of the hook 32 and nose 40 the spring 35 will rock the trigger 20 rearwardly a slight 15 amount sufficient to separate the set trigger 29 from the regular trigger 20 as shown in Fig. 2. It will be noted at this time that although the trigger 20 has been moved forwardly no movement of the sear lever 18 will 20 take place the cam 23 being merely drawn downwardly away from the lower edge of the frame 9.

In order to discharge the gun a slight amount of pressure is applied to the finger 25 piece of the set trigger sufficient to disengage the hook 32 and nose 40 whereupon the energy stored up in the spring 35 will move the trigger 20 quickly rearwardly, the cam 23 contacting with the edge of the frame 9 30 to force the sear lever 18 downwardly thereby disengaging the sear nose 17 from the cocking piece 16 to permit the firing pin to move forward to fire the cartridge.

It is to be noted that a relatively small 35 amount of movement of the set trigger is required to disengage the hook 32 from the nose 40 and the energy stored in the spring 35 is sufficient to afford practically an instantaneous disengagement of the cocking 40 piece and sear nose. In order to vary the amount of contact between the beveled nose 40, and the rear edge of the hook 32 the adjusting screw 33 is provided. If the screw 45 is backed downwardly from the position shown in Fig. 2 a greater area of bearing surface will be provided requiring a greater movement of the set trigger to fire the gun. The amount of bearing surface determines to 50 a great extent the sensitiveness of the set trigger, and practically any degree may be obtained by means of the adjustment of the screw 33.

As has been set forth previously the sear block 38 is pivoted and adjustable to various 55 positions and the reasons for providing this construction will now be set forth. As stated previously the main frame 9 of the firearm and the trigger guard frame 15 are set in the stock 11 which is properly recessed 60 to receive these parts. In the fabrication of the stock the recesses and slots vary perceptibly in dimensions allowing the parts to fit in the stock a greater or less amount depending upon the depth of the recesses. 65 These variations will obviously affect the

sensitiveness of the set trigger and to compensate for these variations the sear block 38 is made adjustable and when the components are in place and securely fastened the proper adjustment and position can be 70 readily obtained by the adjustment screw 41. When properly adjusted no further attention will be required unless other variations or changes have set in after the proper adjustment has been determined. This is an 75 important feature of the present invention as it allows set triggers to be applied to guns already in use or the process of manufacture without any change in the parts. Any variations in the recesses formed in the stock 80 are readily compensated for and practically any degree of sensitiveness of the set trigger which is consistent with safety may be readily obtained at will.

While the form of mechanism herein 85 shown and described is admirably adapted to fulfill the objects primarily stated it is to be understood that it is not intended to confine the invention to the one form of embodiment herein shown and described as it 90 is susceptible of embodiment in various forms all coming within the scope of the claims which follow.

What is claimed is:

1. In a trigger mechanism for firearms, a 95 main trigger, a set trigger pivoted upon the main trigger, a cocking piece, a sear lever in engagement with the cocking piece, means under control of the main trigger for disengaging the said sear lever and cocking piece 100 and spring impelled means under control of the set trigger for actuating the main trigger.

2. In a trigger mechanism for firearms, a 105 main trigger, a set trigger pivoted upon the main trigger, a cocking piece, a sear lever in engagement with the cocking piece, means under control of the main trigger for disengaging the said sear lever and cocking piece and spring impelled means, interposed 110 between the main trigger and a stationary abutment, under control of the set trigger for actuating the main trigger.

3. In a firearm, a manually actuated main 115 trigger for effecting the firing of said firearm, power means for actuating said main trigger comprising a compression spring interposed between said main trigger and a fixed abutment, and a second trigger for controlling said power means.

4. In a trigger mechanism for firearms, a 120 main trigger, a set trigger pivoted upon the main trigger, a spring interposed between the main trigger and a fixed abutment, means whereby adjustment of the said main trigger will store up energy in the said spring and a device for holding the set trigger in its adjusted position.

5. In a trigger mechanism for firearms, a 125 main trigger, a set trigger pivoted upon the

- main trigger, a spring interposed between the main trigger and a fixed abutment, means whereby adjustment of the said main trigger will store up energy in the said 5 spring, an adjustable sear block, means for holding the set trigger in its adjusted position, said means comprising a hook integral with the set trigger engageable with the adjustable sear block.
- 10 6. In a trigger mechanism for firearms, a trigger frame, an adjustable sear block, mounted on the said trigger frame, a main trigger, a set trigger carried by the main trigger, a hook carried by the set trigger 15 adapted to engage with the adjustable sear block and means for regulating the bearing surface between the said hook and sear block.
7. In a trigger mechanism for firearms, 20 a trigger frame, an adjustable sear block mounted on the said trigger frame, a main trigger, a set trigger carried by the main trigger, a hook carried by the set trigger adapted to engage with the adjustable sear 25 block, a spring for holding the hook in engagement with the sear block and separate and independent means for adjusting the said set trigger and adjustable sear block.
8. In a trigger mechanism for firearms, 30 a trigger frame, an adjustable sear block mounted on the said trigger frame, a main trigger, a set trigger adjustably carried by the main trigger, means for holding the set trigger in engagement with the sear block and spring impelled means for causing a 35 separation of the set and main triggers after the set trigger has been adjusted.
9. In a firearm, a stock provided with a recess, a main frame adapted to be secured 40 in said recess, main and set triggers carried by the said frame, a sear block, means carried by the set trigger for engaging the sear block when in its adjusted position, and mechanism for compensating for the 45 variations in the recess to obtain the proper relation between the said sear block and means.
10. In a firearm, a stock provided with a recess, a trigger frame adapted to be secured 50 in the said recess, a main trigger, a set trigger carried by the main trigger, a
- sear block carried by the trigger frame, means carried by the set trigger for engaging the set trigger with the sear block, and mechanism for compensating for the 55 variations in the recess to obtain the proper relation between the said sear block and said means.
11. In a firearm, a main trigger formed with a depression, a spring-urged housing having a conoidal end normally engaging the said depression, and means insuring the proper alignment of the said depression and conoidal end when they become disengaged upon movement of the main trigger from its normal position.
12. In a firearm, a main trigger formed with a depression, a spring-urged member having a conoidal end normally engaging the said depression, and means insuring the proper alignment of the said depression and conoidal end when they become disengaged upon movement of the main trigger from its normal position.
13. In a firearm, a manually actuated main trigger for effecting the firing of said firearm, power means for actuating said main trigger comprising a compression spring interposed between said main trigger and a fixed abutment, and a second trigger 75 carried by the first mentioned trigger for controlling said power means.
14. In a firearm, in combination, a main trigger for controlling the firing of said firearm, power means interposed between 80 said main trigger and a fixed abutment, a second trigger carried by the main trigger and means adapted to cooperate with said second trigger for preventing said power means from moving said main trigger.
15. In a firearm, in combination, a frame, a main trigger for controlling the firing of said firearm, power means interposed between 85 said main trigger and a fixed abutment, a second trigger carried by the main trigger, and means mounted in said frame adapted to cooperate with said second trigger for controlling said power means.

In witness whereof I have signed my name this 19th day of April, 1923.

CHARLES H. BARNES.
